UNITED STATES PATENT OFFICE.

ELI FRANKLIN COLBY, OF LAKE MILLS, IOWA.

RADIATOR FAN.

Application filed August 8, 1922. Serial No. 580,511.

To all whom it may concern:

Be it known that I, ELI F. COLBY, a citizen of the United States, and a resident of Lake Mills, in the county of Winnebago and State of Iowa, have invented certain new and useful Improvements in Radiator Fans, of which the following is a specification.

This invention relates to improvements in the construction of radiator fans for internal combustion engines.

My invention relates to fans, particularly adapted for use in connection with the radiators of internal combustion engines, and has for its object to provide certain improvements in the construction of the same as will be hereinafter more definitely pointed out and claimed, reference being had to the accompanying drawings, in which:—

Figure 1 is a view in front elevation of a fan when applied, said fan embodying the present invention and the blades being partly broken away.

Figure 2 is a transverse sectional view of the fan.

Figure 3 is an outside elevation of the pulley by which the fan blades and associated mounting means are carried.

Figure 4 is a sectional view taken on the line 4—4 of Figure 2.

Figure 5 is an outside elevation of the inner fan blade supporting housing or casing.

Figure 6 is a view in side elevation of the ring gear employed for adjusting the fan blades and for locking them in adjusted position.

Figure 7 is a detail view illustrating the manner in which the ring gears serve to lock the fan blades in adjusted positions.

Like reference numerals refer to like parts throughout the drawings.

Referring to the drawings in detail, B indicates generally the forward portion of the engine housing or casing usually employed for supporting the associated ventilating fan, P indicates the pulley by which the fan is driven, and C indicates a casing or housing which supports the fan blades B¹. The pulley P preferably consists of a casting comprising a drum-like portion 10 which has its outer periphery beveled and which has formed at each end an annular retaining flange 11. One end of the drum 10 has formed upon its inner periphery an annular flange 12 which has formed therewith a journaling sleeve 13, said sleeve having provided upon its inner periphery an annular groove 14 preferably semi-circular in shape as shown. The groove 14 communicates with a duct 15, said duct being closed at its outer end by a screw plug 16. A bolt 17 is extended through the sleeve 13 and threaded into the casing B, as shown, and interposed between the bolt and sleeve 13 are a pair of bushings 18 and 19, the opposing ends of said bushings when positioned being spaced, and said space occurring in registry with the annular groove 14 in the inner periphery of the sleeve 13. Each bushing 18 and 19 is provided at its outer end with a flange 20, the flange of the bushing 18 abutting the head 21' of the bolt 17, while the flange 20 of the bushing is interposed between the associated end of the sleeve 13 and the engine housing B.

The flange 12 of the drum 10 is formed upon its outer side with the annular extension 21 within which the head of the bolt 17 is disposed.

The casing C comprises the two sections 22 and 23. The section 22 is a circular plate 24 having formed upon its outer face and about its periphery a flange 25, the inner periphery of said flange being preferably hexagonal, as shown in Figure 5. The section 22 is secured to the annular extension 21 of the pulley P by the means of screws 26, and the plate 24 of the section 22 is provided upon its outer face with a central boss 27. The section 23 of the casing C corresponds in diameter to the section 22 and consists of a plate having formed about its outer periphery and upon its inner face an annular flange 28 which is provided upon its inner face with four semi-circular recesses as at 29, said recesses being adapted to be brought into registering relation with recesses 30 formed upon the similar face of the flange 25 of section 22. The inner face of the section 23 is also provided with a central boss 23' which is provided with a longitudinally extending central bore, as shown. The section 23 is held in position by a circular plate 31, said plate being formed upon its outer face with a central boss 32 through which there extends a stem 33, said stem terminating at its outer end in a thumb screw head 34 and being extended through the boss 23',

its inner end being threaded through the boss 27 carried by the section 22.

Each fan blade B¹ is preferably made of sheet metal and one end thereof is rolled 5 upon itself to provide a hollow stem portion 35 which is adapted to rotatably fit within a pair of registering recesses 29 and 30 of the casing sections 22 and 23. Upon the inner end of each fan blade stem 35 there is 10 loosely fitted a pinion 36, each pinion having its inner edge or side formed with a plurality of semi-circular notches 37. The notches 37 are arranged in sets preferably three notches constituting a set and each of 15 said notches of a set being diametrically opposed to a notch of the other set upon the fan pinion. A pin 38¹ is extended through each of the fan blade stems 35 at a point adjacent its inner end and said pin being so 20 disposed that its ends will be adapted to be brought into diametrically opposed notches 37 formed in the associated pinion 36.

Upon the inner face of the section 23 there are also formed the gear teeth 38 adapted to 25 form a gear ring which may be brought into mesh with each of the pinions 36.

Within the casing C there is positioned a coil spring C¹ which may consist of two or 30 more convolutions, as shown, and which is of a suitable diameter so that the free ends 35 of the fan blade stems 35 may engage thereon.

The coil spring 33 may be held in its applied position with suitable tangs as at 39 35 which extend from ears 40 formed upon the inner side of the perimeters of the flange 28 of the casing section 23 respectively.

In use the fan is mounted upon an internal combustion engine, and a belt P¹ is employed for rotating the casing C. Oil may 40 be introduced through the duct 15 whereby to lubricate the bolt 17. In case it is desired to change the position of the fan blades B¹, any fan blade may be adjusted individually 45 by pressing it inwardly against the tension of the spring C¹ and then rotating it to shift its pin 38¹ so that it may engage in a different pair of aligned notches 37, the arrangement of said notches being such, as shown in 50 Figure 7, that any fan blade may be shifted to assume either a neutral position, or a position to force air either forwardly or backwardly, as desired. Should it be desired to change the pitch of all of the blades simultaneously 55 in either direction, then by turning the stem 33 slightly to loosen the plate 31 the section 23 will be free to rotate, carrying with it the gear teeth 38 which will 60 rotate the pinions 36 simultaneously thereby correspondingly adjusting the fan blades B¹.

While I have shown and described the preferred form of my invention, I wish it to be understood that I am aware of the fact that the construction, combination and arrangement of parts may be changed by those

skilled in the art without departing from the spirit of the invention, as indicated by the appended claims.

I claim:—

1. In a fan structure of the character described, annular casing having a plurality of radial openings, a plurality of fan blades, one for each of said openings, said fan blades in each instance having an inner end stem portion adapted to be extended within 75 the opening of the casing, a pinion carried upon the inner end of each fan blade stem, and a ring gear carried by the casing adapted to mesh with said pinions whereby to lock the fan blades against turning movement.

2. In a fan structure of the character described, an annular casing having a plurality of radial openings, a plurality of fan blades, one for each of said openings, said 85 fan blades in each instance having an inner end stem portion adapted to be extended within the opening of the casing, a pinion carried upon the inner end of each fan blade stem, a ring gear carried by the casing 90 adapted to mesh with said pinions whereby to lock the fan blades against turning movement, and means whereby the ring gear may be rotated for rotating said fan blades in unison.

3. In a fan structure of the character described, an annular casing having a plurality of radial openings, a plurality of blades, one for each of said openings and rotatably mounted therein, a pinion loosely mounted 100 upon the inner end of each fan blade and having notches formed upon its inner side, a transverse pin carried by the inner end of each fan blade adapted to engage in the notches of the associated pinion, means for yieldably pressing the fan blades outwardly, and means for locking the pinions against turning movement.

4. In a fan structure of the character described, an annular casing having a plurality 110 of radial openings, a plurality of blades, one for each of said openings and rotatably mounted therein, a pinion loosely mounted upon the inner end of each fan blade and having notches formed upon its inner side, a transverse pin carried by the inner end of each fan blade adapted to engage in the notches of the associated pinion, means for yieldably pressing the fan blades outwardly, and a ring gear for locking the pinions 120 against turning movement.

5. In a fan structure of the character described, an annular casing having a plurality of radial openings, a plurality of blades, one for each of said openings and rotatably mounted therein, a pinion loosely mounted 125 upon the inner end of each fan blade and having notches formed upon its inner side, a transverse pin carried by the inner end of each fan blade adapted to engage in the 130

- notches of the associated pinion, a coil spring positioned within the casing and adapted to engage the inner ends of said fan blades for yieldingly holding the fan against 5 inward movement, and means for locking said pinions against turning movement.
6. In a fan structure of the character described, an annular casing having a plurality of radial openings, a plurality of blades, one 10 for each of said openings and rotatably mounted therein, a pinion loosely mounted upon the inner end of each fan blade and having notches formed upon its inner side, a transverse pin carried by the inner end of 15 each fan blade adapted to engage in the notches of the associated pinion, a coil spring positioned within the casing and adapted to engage the inner ends of said fan blades for yieldingly holding the fan against inward movement, and adjustable means for 20 locking said pinions against turning movement.
7. A fan construction of the character described, comprising a pulley having an annular extension formed upon one end thereof, a casing secured to said annular extension, said casing comprising a circular inner section and a similar outer section, said sections being adapted to permit a plurality 25 of fan blades to be rotatably supported therebetween and radially thereto, and means for securing said sections to the extension of the pulley.
8. A fan construction of the character described, comprising a pulley having an annular extension formed upon one end thereof, a casing secured to said annular extension, said casing comprising a circular inner section and a similar outer section, said sections being adapted to permit a plurality 30 of fan blades to be rotatably supported therebetween and radially thereto, the first named 40
- section being bolted into the annular extension of the pulley and being formed on its outer face with a central boss, and a bolt 45 extending centrally through the outer section and threaded into said boss whereby the two sections are secured together.
9. A fan construction of the character described comprising a pulley having an extension formed at one end thereof, a casing comprising a pair of circular sections, said sections being adapted to permit a plurality of fan blade stems to be rotatably supported therebetween, and means for clamping said 50 sections together and securing the same to the extension of said pulley.
10. A fan construction, comprising an annular casing, a plurality of fan blades rotatably supported by said casing and extending 55 radially thereof, said fan blades being adapted to move inwardly with respect to said casing, a single spring for yieldingly holding all of said fan blades against inward movement, and means cooperating with said 60 spring for normally holding said fan blades against rotation.
11. A fan construction, comprising an annular casing, a plurality of fan blades rotatably supported by said casing and extending 65 radially thereof, said fan blades being adapted to move inwardly with respect to said casing, a single spring for yieldingly holding all of said fan blades against inward movement, and a pin carried by each 70 fan blade adapted to engage in cooperative notches when pressed outwardly for holding its fan blade against rotation.
12. A fan structure, comprising a casing, a plurality of fan blades radially mounted 75 therein, means permitting separate axial adjustment of said fan blades, and means for effecting axial adjustment thereof in unison.

ELI FRANKLIN COLBY.
